UNITED STATES PATENT OFFICE.

HENRY P. ROBERTS, OF BOSTON, MASSACHUSETTS, ASSIGNOR TO DORSEY MANUFACTURING COMPANY, OF BOSTON, MASSACHUSETTS, A CORPORATION OF MASSACHUSETTS.

DESIGN FOR A KEY-RING.

42,882.

Specification for Design.

Patented Aug. 13, 1912.

Application filed June 17, 1912. Serial No. 704,241. Term of patent 3½ years.

To all whom it may concern:

Be it known that I, HENRY P. ROBERTS, a citizen of the United States, residing in Boston, in the county of Suffolk and Commonwealth of Massachusetts, (whose post-office address is Homestead street, Boston, Massachusetts,) have invented a certain new, original, and ornamental Design for a Key-Ring, of which the following, together with the accompanying drawing, forming a part thereof, is a specification.

The illustration shows a view in elevation of my design for a key ring.

I claim:

The ornamental design for a key ring as shown.

HENRY P. ROBERTS.

Witnesses:

GEORGE CLARENDON HODGES,
CHARLES W. SWETT.
